190,500

BOOKCASE

David Harper, 2122 Webster Ave., Pittsburgh, Pa.

Filed Apr. 29, 1960, Ser. No. 60,370

Term of patent 14 years

(Cl. D33—2)

FIG. 1.

FIG. 2.

FIG. 3.

FIGURE 1 is a perspective view of a bookcase, according to the present invention, showing my new design;

The side not shown is like the side shown while the back of the article is conventional.

I claim:

The ornamental design for a bookcase, as shown and described.
